REFRIGERATING SYSTEM.

1,415,399.

Specification of Letters Patent.

Patented May 9, 1922.

Application filed July 5, 1921. Serial No. 482,459.

To all whom it may concern:

Be it known that I, WALTER W. ROBINSON, a citizen of the United States, residing in Beloit, Rock County, Wisconsin, have 5 invented certain new and useful Improvements in Refrigerating Systems, of which the following is a specification.

My present improvements relate more particularly to systems for inducing refrigeration through compression, condensation and expansion of a refrigerating medium, for instance ammonia gas, NH₃.

Its principal objects are to provide a system or apparatus which has a high factor 15 of safety when installed, one in which there may be a notable reduction of the effective relative size or capacity of the prime mover over such as have been ordinarily employed, and in which severe strains upon the prime 20 mover in starting are avoided, these advantages arising chiefly from provisions which result in what may be a substantial equalization of the pressure at particular times between the high-pressure and low-pressure sides of the device or in any event which result in reduction of the pressure in 25 the high-pressure side. A further object is to attain the mentioned equalization or reduction of pressure automatically as the 30 occasion arises therefor. It is an object also to provide an automatic control for the gas-cooling medium, usually a liquid and ordinarily water, and, according to the specific application herein illustrated, to provide 35 means under the control of the gas-cooling medium for normally maintaining the circulation of the gas-cooling medium, and also for throwing into effect a shunt or by-pass for the refrigerating medium between the 40 high-pressure and low-pressure sides when the supply of the gas-cooling medium is cut off or materially reduced. A further object is to provide a device in which the desired safety against undue internal pressure 45 may be had without loss of the refrigerating medium. The general object is to provide a device of the character described which is highly efficient, safe and economical, and which may well be in the form of a small 50 machine adapted for household use when so desired.

In the accompanying drawings, which form a part hereof, the single figure represents the system or device complete, but in 55 a substantially diagrammatic way as to size

and arrangement of the parts, the several parts being shown as widely separated for clearness of illustration.

My improved system as illustrated herein includes a circuit for the refrigerating medium, having a condenser and means for supplying a gas-cooling medium thereto and which for description may be assumed to be water, a compressor, and a pressure-regulating valve for establishing a high-pressure 60 side and a low-pressure side, all broadly according to hitherto well known practice. That is to say, so far as the units are considered broadly it is old to provide a compressor as 10, a motor as 11 for driving it, 70 a pipe coil as 12 in a water tank 13, a pressure-regulating valve 14, an expansion coil 15, and pipes 17 and 18 leading back to the compressor forming a circuit for the refrigerating medium. 75

According to the particular form or compressor 10 illustrated the gaseous refrigerating medium passes through the spring-controlled poppet valve 17 in the piston and thence through the similar valve 18 into 80 the pipe connection 19 and thence through the condenser, etc., returning to the chamber 20 of the compressor through the pipe 18 as shown.

The pressure-regulating valve 14 may be 85 considered as of any approved form and is a device which impedes the flow of the refrigerating medium whereby the desired high pressure is obtained in the condenser coil 12 and, in general, in the pipe means 90 between the valve 14 and the compressor at the connection 19, this part of the system being the high-pressure side. The low-pressure side of the system is the pipe means including the expansion coil 15 and the 95 pipes directly connected to it, and is that part of the system which is operatively between the valve 14 and the chamber 20 of the compressor in the direction of the flow. 100

The pressure upon the gas together with the cooling effect of the gas-cooling medium in the condenser tank 13 causes the gas to liquify or condense in volume, and its escape from the valve 14 to the relatively 105 large expansion coil 15 causes the medium to resume its gaseous form from the liquid or to expand from the compressed form accompanied by the absorption of heat units in the vicinity of the coil 15, thereby 110

reducing the temperature in the refrigerator 21, such abstracted heat units being carried by the refrigerating medium to the compressor and thence to the condenser 5 and there abstracted by the gas-cooling medium constantly being supplied to the tank and discharged through the pipe 23. In respect to the sequence of operations and arrangement of units the foregoing description is in accordance with what is well known.

Assuming the gas-cooling medium to be water in the device illustrated, it is supplied by a pipe 25 and enters the valve 26 passing 15 therefrom through the pipe 27. Between the inlet and outlet of the valve 26 is the valve head 28 on the stem 29 adapted to be moved up and down and the valve closed and opened through the rocker arm 30 having 20 an operative connection with the centrifugal governor 31 actuated by the motor 11 as by means of a belt 32. On starting the motor the weights of the governor 31 spread apart lifting the end 32 of the rocker 25 arm 30 and depressing the other end thus opening the valve at 28 and allowing water to flow through the valve and into the pipe 27. As soon as the motor stops the valve at 28 is automatically closed through action of 30 the governor and the supply of water is cut off.

From the pipe 27 the water flows to a chamber 35 of a by-pass control device, the chamber 35 being defined on one side by a 35 flexible diaphragm 36, and from this chamber 35 the water passes through the pipe 37 to the water-pressure-regulating valve 38 and thence through the pipe 39 to the tank 13. Between the intake and outlet of the 40 valve 38 is a spring-controlled valve head 40 adapted to be raised by the water pressure to permit the desired flow. By means of the screw 41 the spring pressure upon the valve head 40 may be varied whereby the desired 45 back pressure in the pipe 37 and consequently in the chamber 35 may be adjusted to and maintained substantially at a given amount during normal operation. Thus, although the water pressure in the pipe 25 50 may be quite high the regulating valve 38 may be adjusted so that the pressure in the chamber 35 may be quite low, and regardless of the pressure in the pipe 25 that in the chamber 35 may be predeterminedly 55 lower if desired.

Pipe means are provided forming a by-pass or shunt between the high-pressure side and the low-pressure side of the refrigerating circuit. The by-pass pipe 45 leads from 60 the high pressure side to a chamber 46 in the by-pass control device and thence through the pipe 47 to the connection 48 which is common to the three pipes 17, 18 and 47 and places them in communication with each 65 other. It is thus clear that pressure from

the high-pressure side may be diverted to the low-pressure side of the system and the pressure between the two sides equalized if desired or at least the pressure of the high-pressure side materially reduced.

The valve at 50 controls the flow of the refrigerating medium into the chamber 46. The valve 50 is shown as closed in the drawings, which is its normal position when the refrigerating system is in normal operation. 75 The valve 50 is held closed partly by the water pressure in the chamber 35 which moves the diaphragm 36 upward slightly, thus moving the pressure-transmitting pin 52, the bar 53, the short rod 54, the diaphragm 55 and finally the valve 50, the diaphragm 55 constituting one wall of the chamber 46. The diaphragm 36 has a relatively large area compared with that of the diaphragm 55, and therefore a relatively low 80 water pressure in the chamber 35 will balance a relatively high pressure in the pipe 45 and chamber 46 reacting against it.

The bar 53 is mounted loosely enough at 58 for slight swinging movement, and its 90 other end is carried by a headed bolt 59 having the expansion spring 60 adapted to force the bar 53 in an upward direction as the device is illustrated. The pressure of the spring 60 may be regulated by the nut 95 61. The function of the bar 53 is to co-operate with the pressure of the water in the chamber 35 in maintaining the valve 50 closed, and accordingly the water pressure in chamber 35 may be considerably reduced 100 over what would otherwise be required and the by-pass control valve at 50 is rendered more sensitive to a default of the water pressure system. Thus, for instance, the pressure of the spring 60 may be almost sufficient 105 to maintain the valve 50 closed under the normal pressure in the pipe 45, and the added pressure of the water in the chamber 35 may be only such a small number of pounds per square inch as will, together with the 110 pressure of the spring 60, maintain the valve 50 closed at normal pressures in the pipe 45.

The desideratum in this respect is to have 115 the effective pressure in the chamber 35 plus the effective pressure of the spring 60 at least equal to the pressure in the pipe 45 effective to open the valve at 50 and thus maintain the desired pressure on the high-pressure side of the system during normal 120 operation, and at the same time these relative pressures are such that should the pressure in the pipe 45 become materially greater than the predetermined normal pressure the valve 50 will be opened allowing the excess pressure to escape through the chamber 46 and pipe 47 into the low-pressure side.

According to such construction so long as 125 water under sufficient pressure is flowing through the system including the chamber 130

35 the valve at 50 will remain closed, but on failure of the predetermined pressure of the water supply in the chamber 35, either by an accidental or other 5 obstruction in the conduit or through the stoppage of the motor, the diaphragm 36 will fall, allowing the pressure in the pipe 45 to escape into the chamber 46 and pipe 47, and thus reduce the pressure in the high-pressure side to the extent permitted by the 10 spring 60, but in any event to such a material extent as to provide the desired safety. Furthermore, should the pressure in the high-pressure side for any reason develop 15 materially beyond the normal amount such pressure will over come the resistance of the spring 60 and the water pressure in chamber 35 causing such reduction of pressure as will bring that of the high-pressure side back to 20 normal.

The water-pressure-regulating valve 40 is designed to maintain substantially constant pressure in the by-pass control device 35. Since such pressure might be maintained 25 through slight leakage at the water valve 28, or when the valve 28 is opened to permit a small flow of water to the valve 40 while not supplying enough flow to provide the desired quantity of cooling liquid in the 30 tank 13, I provide means for insuring the opening of the valve 50 to allow for pressure escape to meet such conditions. The means illustrated are the provision of a leakage hole 65 in a wall of the inlet chamber of the 35 valve 38, which hole 65 opens into a passage 66 in communication with the discharge chamber of the valve 38. A conically-pointed screw 67 controls the flow through the hole 66. If, therefore, the water pressure 40 in the chamber 35 is insufficient to open the valve 40 the water passing through the system will escape through the hole 65 and the diaphragm 36 will therefore remain down and the valve 50 will remain open whereby 45 the pressure in the pipe 45 is maintained at only such an amount as is determined by the spring 60, namely a pressure which is always low enough for safety.

The check valve 69 in the pipe 17, and 50 preferably located close to where the by-pass pipe as 47 is in communication with the low-pressure side, prevents the excess pressure from the by-pass from entering the expansion chamber, as the coil 15, and thus avoids 55 interference with the heat-absorbing work being done by the refrigerant in that coil, and, furthermore, it avoids the necessity of reducing the pressure, by the suction of the compressor, in the relatively large space defined by the expansion coil, thus saving time 60 and energy in restoring the normal flow through the circuit.

In charging the device the valve 70 is closed and the valve 71 is opened to the 65 outer air. The valve 72 remains open.

Thereupon the compressor is put into operation pumping the air or gas out of the refrigerating system and creating a substantial degree of vacuum therein. Thereupon the valve 71 is closed and the valve 70 is 70 opened, and thereupon the valve 73 is opened and the charge of gas flows from the container 74 into the chamber 20 of the compressor and into the low-pressure side of the system and also into the high-pressure side 75 through the pipe 45 if the valve 50 be open. In any event, the operation of the compressor soon forces the gas throughout the circuit. Thereupon the valve 73 is closed and the container 74 may be removed. 80

Since the pressure in the high-pressure side becomes materially reduced by escape through the by-pass as soon as the motor stops, the subsequent starting of the motor is against a relatively light load, and this 85 prime mover may therefore be of less capacity than if it had to start against the full lead, thus saving space as well as cost in installation and use. The device is also safe from explosive pressures, and this is accomplished without loss of the refrigerating medium. The automatic control of the gas-cooling medium promotes both safety and economy, and the control of the safety-by-pass valve by the supply of gas-cooling me- 90 dium provides means for automatically maintaining the system against dangerous pressures due to a failure properly to cool the gas. Various other advantages from such provisions will readily be appreciated 95 by those skilled in the art.

While I have thus illustrated and described a highly efficient embodiment of these improvements the invention is not limited to the specific means illustrated for obtaining the desired results, and reference should be had to the appended claims to determine the scope of the improvements herein set forth. 105

I claim:

1. In a refrigerating system, the combination of a prime mover, a compressor operated thereby, means forming a passage-way from the outlet of the compressor to the inlet thereof, a valve in said passageway, 115 means including means under the control of the prime mover for closing said valve when the prime mover is operating at a predetermined rate.

2. In a refrigerating device of the character described, the combination of a condenser, means for supplying a gas-cooling medium to the condenser, means for forcing gas under pressure through the condenser and back to the gas-forcing means in a circuit, a prime mover for operating the gas-forcing means, means forming an expansion chamber forming part of said circuit, the same being beyond the condenser in the direction of flow of the refrigerating gas, 125 130

- means for impeding the flow of gas through said circuit to form a high-pressure side and a low-pressure side therein, means forming a by-pass between the high-pressure side 5 and the low-pressure side of said circuit, valve means in said by-pass, and means under the control of the prime mover for releasing said valve to open the same when the prime mover is operating at a rate which 10 is below a predetermined rate.
3. In a refrigerating device of the character described, the combination of a condenser, means for supplying a gas-cooling medium to the condenser, means for forcing 15 gas under pressure through the condenser and back to the gas-forcing means in a circuit, means forming an expansion chamber forming part of said circuit, the same being beyond the condenser in the direction of the 20 flow of the refrigerating gas, means for impeding the flow of gas through said circuit to form a high-pressure side and a low-pressure side therein, means forming a by-pass between the high-pressure side and the low- 25 pressure side of said circuit, valve means in said by-pass, and means under the control of the gas-cooling medium for automatically opening said valve means when the supply of the gas-cooling medium is materially de- 30 creased.
4. In a refrigerating device of the character described, the combination of a condenser, means for supplying a gas-cooling medium to the condenser, means for forcing 35 gas under pressure through the condenser and back to the gas-forcing means in a circuit, means forming an expansion chamber forming part of said circuit, the same being beyond the condenser in the direction of the 40 flow of the refrigerating gas, means for impeding the flow of gas through said circuit to form a high-pressure side and a low-pressure side therein, means for forming a by-pass between the high-pressure side and the 45 low-pressure side of said circuit, valve means in said by-pass, means for holding said valve closed against pressure in the high-pressure side which is less than normal, auxiliary means under the control of the cooling medium cooperating to hold said valve closed 50 against the normal pressure in the high-pressure side.
5. In a refrigerating device of the character described, the combination of a condenser, means for supplying a gas-cooling 55 medium to the condenser, means for forcing gas under pressure through the condenser and back to the gas-forcing means in a circuit, means forming an expansion chamber forming part of said circuit, the same being 60 beyond the condenser in the direction of the flow of the refrigerating gas, means for impeding the flow of gas through said circuit to form a high-pressure side and a low-pressure side therein, means forming a by- 65 pass between the high-pressure side and the low-pressure side of said circuit, valve means in said by-pass, means for holding said valve closed against pressure in the high-pressure side which is less than normal, auxiliary 70 means under the control of the cooling medium cooperating to hold said valve closed against the normal pressure in the high-pressure side, and means for regulating the effective valve-holding pressure of the cool- 75 ing medium.
6. In a refrigerating system, the combination of means forming an operative circuit for the refrigerating medium, said circuit having means establishing a high-pressure 80 side and a low-pressure side, means forming a by-pass between the high-pressure side and the low-pressure side, and valve means under the control of the gas-cooling means for maintaining the valve closed against normal pressure in the by-pass and for automatically relieving pressure in the by-pass when such pressure rises to a predetermined amount.

WALTER W. ROBINSON.
